Patented Nov. 8, 1955

176,045

CHAISE LONGUE

Jack Sherman, Los Angeles, Calif.

Application December 27, 1954, Serial No. 33,705

Term of patent 3½ years

(Cl. D15—1)

Fig. 1.

Fig. 2.

Fig. 1 is a front perspective view of a chaise longue, showing my new design; and

Fig. 2 is a rear perspective view.

The rung of the chair is rectangular with rounded edges.

I claim:

The ornamental design for a chaise longue, as shown and described.
